United States Patent

Des. 236,941
Patented Sept. 30, 1975

236,941

CLAMP

Robert G. Seavers, Wheeling, Ill., assignor to Baxter Laboratories, Inc., Deerfield, Ill.

Filed Mar. 14, 1974, Ser. No. 451,327

Term of patent 14 years

Int. Cl. D8—08

U.S. CL. D8—73

FIG. 1

FIG. 2

FIG. 3

FIG. 4

FIG. 5

FIG. 6

FIG. 7

FIG. 1 is a perspective view of a clamp constructed in accordance with the present invention.

FIGS. 2, 3, 4, and 5 are elevational views of the clamp of FIG. 1 as seen from each of its sides.

FIG. 6 is a top view of the clamp of FIGS. 1-5.

FIG. 7 is a bottom view of the clamp of FIGS. 1-6.

I claim:

The ornamental design for a clamp, as shown.
